UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,835, dated November 5, 1895.

Application filed September 30, 1895. Serial No. 564,221. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of a series of ornaments formed of an open wreath of leaves with an ornamental figure having a flaming torch-like top placed in the center of said open wreath, as represented in the accompanying drawing, said ornaments being placed at regular distances apart over the surface of the paper.

The border of the design is formed of similar ornaments connected by festoons of ribbons hanging from ornamental figures at each side of said ornaments, as shown in the drawing.

What I claim is—

1. The design for wall paper herein shown and described.
2. In the design for wall paper, the border herein shown and described.

Witness my hand this 27th day of September, 1895.

CHARLES BOOZ.
